Filed Oct. 11, 1963, Ser. No. 315,718

Claims priority, application France, Jan. 17, 1963, 921,709

11 Claims. (Cl. 9—8)

The present invention is a continuation-in-part of our co-pending patent Application No. 99,212, filed on March 29, 1961, entitled "Floats," now Patent No. 3,114,920, December 24, 1963.

We have described in said earlier application a buoyancy float comprising a rigid envelope surrounding a flexible envelope formed from an impermeable material, said envelopes defining two chambers, the first of which contains a buoyancy mass comprising an elastic fluid under a pressure equal to the hydrostatic pressure corresponding to a predetermined immersion depth and the second of which is in communication with the outside of the float to permit entry of the surrounding liquid into the second chamber when the float is immersed.

An object of the present invention consists in providing floats of the type described, which are easy to manufacture and assemble.

Another object of the present invention consists in providing floats of the type described which can function smoothly and without mishap in the course of repeated immersions and emersions.

Another object of the present invention consists in providing floats of the type described wherein the flexible envelope is substantially protected from the danger of excessive stresses taking place through large pressure differences on opposite faces of said envelope.

Another object of the present invention consists in providing floats of the type described wherein a satisfactory and predictable deformation of said flexible envelope is obtained.

Another object of the invention consists in providing floats of the type described, wherein perforations, provided to put said second chamber in communication with the outside of the float, are positioned with a view to reducing the strains and stresses to which said flexible envelope is subjected when operating the floats.

With these and other objects in view, the present invention concerns floats of the type described wherein the flexible envelope defines said first chamber and the rigid envelope defines said second chamber, the rigid envelope being apertured to establish said communication with the outside of the float.

Other objects of the invention will appear in the course of the following description.

In order to make the above stated objects, as well as other objects of the invention, more readily understood, reference will now be made to the accompanying drawings, which illustrate diagrammatically and by way of an example one embodiment thereof, by means of one figure showing a part elevational part sectional vertical view of a float according to the invention and one figure showing a longitudinal cross-sectional view of a simple valve which may be used in the float.

FIG. 1 of the drawings shows a float having a rigid steel envelope in the shape of a tubular wall 1 assembled by welding at its opposite ends to two dome-shaped closing walls respectively indicated by numerals 2 and 3.

End wall 2 contains a large circular aperture 4 surrounded by an annular flange 6, which is welded to end wall 2 by means of an annular angle-shaped section 5 forming a vertical brim element around aperture 4. To

2

flange 6 is adapted to be fixed by a number of bolts a rigid plate 8 on the internal face of which is fixed a sleeve shaped element 9 which carries a closing element comprising a dome-shaped closing plate 10 adapted to be positioned within the circular aperture 4.

The general shape of plate 10 corresponds to the shape of that portion of the end wall 2 which has been taken away to form aperture 4, so as to provide a smooth transition along the contact line between wall 2 and plate 10. Plate 10 comprises a central hole delimited by an upstanding edge 11. Plate 10 can eventually be manufactured out of the portion which has been cut away from end wall 2 in order to form aperture 4. Rigid plate 8 includes a conical hole 12 situated opposite edge 11, and is adapted to receive on its outerface a shackle 13 for fastening the float to a cable 14.

End wall 3 comprises a central hole, circular in shape, and crowned by a hollow thimble 16 fixed to end wall 3 by weld 17, to form a water-tight seal.

Aperture 4 makes it possible to introduce easily within the rigid envelope a bladder 20 made of impermeable fabric and adapted to be inflated to the shape of said envelope. Bladder 20 carries, at opposite ends projecting metal fittings 21, 22, fastened to its fabric.

Fitting 21 is adapted to fit within hole 12 in rigid plate 8, and comprises a threaded extension 23 through which it can be locked in position by means of screws and washers assembly 24.

Fitting 22, which fits within hollow thimble 16, comprises also a threaded extension 25, and includes an axial bore extending from end to end of said fitting, which bore is normally closed at its outer end by means of screw plug 26; fitting 22 contains an internal valve (not shown) adapted to enable the bladder to be filled by gas under pressure, and to prevent such gas from escaping. Fitting 22 can be locked in position by means of screws 27. A capping piece 28 is screwed on to hollow thimble 16, by means of screw threads provided at the latter's upper end.

The space within the rigid envelope communicates with the exterior through perforations 30 formed within rigid plate 8, and perforations 31-32 arranged in two concentric rings within closing plate 10, sleeve element 9 having also a number of holes 33. Perforations 31-32 are small, so as to avoid damaging or puncturing the bladder when the pressure within said bladder is greater than the external pressure.

At least one ring 35 is welded on a stiffening ring 36 fixed around the tubular wall 1, for handling the float, or for fastening on to it one or several compensating floats. For assembling the float, it is expedient to place the rigid envelope upside down, with the bottom opening facing upwards. Bladder 20, deflated and already assembled to plate 8, is then inserted within said opening, the top end, bearing fitting 22, being inserted first, and coming to nest within thimble 16. Said fitting 22 is then fixed by means of screws 27, and plate 8 is bolted down on flange 6.

Air is then inserted through the valve provided within fitting 22, under a predetermined pressure corresponding, say, to 1200 ft. of water depth, after which plug 26 is screwed down, and capping piece 28 is fixed on to thimble 16, the permanently confined pressurized air applying bladder 20 tightly against the rigid envelope 1-2-3. The float is then ready to be operated.

FIG. 2 shows a longitudinal cross-sectional view of simple valve which may be employed with fitting 22.

This valve comprises a frame 22c which comprises, for example, three thin brackets (two of which are visible) joined at the center to hold a weak spring 22a. A valve cover 22b is supported by the spring 22a so as to normally close opening 22d. When it is desired to introduce gas

3
under pressure into bladder 20, the gas pressure forces 22b away from the opening 22d permitting gas to enter. When the pressure of the gas inside the bladder rises to a point where it is slightly less than the pressure under which gas is being introduced, spring 22a urges cover 22b into its closed position. The unit is now ready for use and cover 22b will prevent any escape of gas during the submersion of the float.

Perforations 31-32 are made sufficiently small to avoid 10 damaging the bladder when inflated. The diameter of these perforations is preferably not greater than twice the thickness of the bladder flexible envelope, and the inner edges of said perforations are preferably chamfered or rounded off, to avoid bringing the bladder in contact with sharp arrises.

Rectangular openings may be used instead of circular 15 perforations, the width of each rectangle, defining each such opening, being preferably not greater than the thickness of the flexible envelope.

In operation, the float, which may be attached on the 20 surface to a submarine pipe in the course of laying, becomes progressively immersed with said pipe, keeping its buoyancy all the while, down to said 1200 ft. depth. As the immersion progresses beyond that depth, the outside 25 water pressure becomes greater than the air pressure within the bladder, and water, entering the rigid envelope through perforations 31-32, begins to find a path between said envelope and bladder 20, and to reduce progressively the air volume within the bladder, according to Boyle's 30 Law. The net upward force on the float decreases therefore from a 1200 ft. depth downward, to become equal to zero at a given depth, and to assume negative values beyond said given depth.

Conversely, when raising the pipe, for inspection or for 35 any other purposes, the float net upward force increases progressively and regains its original value at the same depth of 1200 ft., after which it remains constant until it reaches the surface.

The perforations allowing entry of water in the rigid 40 envelope are preferably positioned as one single group of closely spaced perforations, located at a selected emplacement on said envelope, to enable the bladder to go through the same process of deformation in the course of successive immersions. Said selected emplacement is 45 preferably situated in the vicinity of the lower fitting, so that the bladder portion which will be subjected to reverse curvatures in the course of deformation, is one that will normally have an extra thickness of material to provide a strong fixing point for said fitting.

The float thus described is capable of developing a 50 variable buoyancy, which varies in a predictable manner according to its depth of immersion. It is also capable of being immersed and emersed in succession as often as may be required, with the bladder alternatively contracting and expanding while it remains rigidly fastened at fixed 55 points at opposite ends of the float, any given point of the bladder being thereby subjected to the same stress variation in the course of repeated operations.

What we claim is:

1. A float having a buoyancy adapted to vary automatically in function of its depth of immersion, comprising a rigid envelope and a flexible envelope formed from an impermeable material in the shape of a bladder situated within the rigid envelope, said envelopes defining two chambers, one of the chambers being defined by the bladder which contains and permanently confines a buoyancy mass comprising an elastic fluid under a pressure equal to the hydrostatic pressure corresponding to a predetermined immersion depth, and the second of the chambers being defined by the rigid envelope, said rigid envelope comprising openings to allow the surrounding liquid to penetrate within said second chamber when the float is immersed beyond said predetermined depth, said float comprising an aperture within said rigid envelope for inserting 60

65 said flexible envelope, a closing element for closing said aperture, fastening means for holding said closing element in its closed position and for fastening it to said rigid envelope.

2. A float according to claim 1 wherein said openings are positioned within said closing piece.

3. A float according to claim 1 wherein said openings are circular perforations of a diameter not greater than twice the thickness of the flexible envelope.

4. A float according to claim 1 wherein said openings are chamfered on the periphery of their edges of contact with said flexible envelope.

5. A float according to claim 1 wherein said openings are 15 rectangular in shape, the smaller side of each rectangle being not greater than the thickness of the flexible envelope.

6. A float according to claim 1 wherein the edges of contact of said openings with said flexible envelope are rounded off.

7. An automatically variable buoyancy float comprising:

a rigid envelope in the shape of a surface of revolution formed about a vertical axis, said rigid envelope containing an inflatable bladder made of an impermeable flexible material, said bladder being adapted, when inflated, to assume through swelling the shape of the rigid envelope;

an aperture for inserting said bladder within said rigid envelope, and a closing piece for closing said aperture after insertion of the bladder, said closing piece being adapted to form part of the rigid envelope when in the closing position and including means adapted to fix it in said closing position;

fastening means secured to said bladder for fastening the bladder to said rigid envelope at opposite ends of said vertical axis, at least one of said fastening means protruding outwardly through the rigid envelope;

within one of said protruding fastening means, a duct leading from the exterior to the space confined within the bladder, and a valve disposed within said duct, for retaining a pressurized gas within said space; a plurality of perforations formed through the bottom portion of said rigid envelope in the vicinity of the lower end of said vertical axis, and regularly spaced around said axis, to permit entry of the surrounding liquid within the rigid envelope.

8. An automatically variable buoyancy float according to claim 7 wherein the rigid envelope comprises a vertical tubular wall, closed at top and bottom respectively by two dome-shaped end walls.

9. An automatically variable buoyancy float according to claim 7 wherein the rigid envelope comprises a vertical tubular wall, closed at top and bottom respectively by two dome-shaped end walls and said aperture is formed by cutting away a central circular portion within said lower dome-shaped end wall, said closing piece having a shape corresponding to that of said central portion and comprising said perforations.

10. An automatically variable buoyancy float according to claim 7 wherein said aperture is surrounded by a brim element secured to the rigid envelope, and said closing piece is secured on its outer face to a circular sleeve coaxial with the float along a rim of said sleeve, said sleeve being secured at its opposite rim to a rigid plate adapted to be fastened to said brim element, said rigid plate and closing piece having respective central openings coaxial with the float, through which openings the lower of said fastening means is adapted to protrude on the outer face of the rigid plate and to be secured to said rigid plate, said rigid plate comprising through holes forming passageways to the surrounding water.

11. An automatically variable buoyancy float according to claim 7 wherein said valve-containing fastening means projects outwardly through a central opening

formed within the rigid envelope at the top end of said vertical axis, and fits snugly within a hollow thimble tightly sealed to the rigid envelope around said opening, said fastening means having a threaded extension adapted to protrude outwardly through the upper end of said thimble for securing said fastening means within said thimble.
